[57] CLAIM

The ornamental design for the interior surfaces of a snow tool blade, as shown and described.

DESCRIPTION

FIG. 1 is a front right perspective view of the interior surfaces of a snow tool blade in accordance with the present invention;

FIG. 2 is a front elevational view thereof;

FIG. 3 is a left front perspective view thereof; and,

FIG. 4 is front elevational view of a second embodiment of the design shown in FIGS. 1–3 with the only difference residing in the uninterrupted appearance at the center of the top edge of the blade;

The broken lines showing the exterior of the snow tool blade are for illustrative purposes only and form no part of the claimed design.
